UNITED STATES PATENT OFFICE.

JAMES P. GARDNER, OF CHICAGO, ILLINOIS, ASSIGNOR TO THE REDUCING MACHINE COMPANY, A CORPORATION OF ILLINOIS.

BODY-TREATMENT MACHINE.

1,305,595.

Specification of Letters Patent.

Patented June 3, 1919.

Application filed July 6, 1914. Serial No. 849,242.

To all whom it may concern:

Be it known that I, JAMES P. GARDNER, a citizen of the United States, residing at Chicago, in the county of Cook and State of Illinois, have invented certain new and useful Improvements in Body-Treatment Machines, of which the following is a specification.

This invention relates to a machine for producing a massaging or rolling action on the body or limbs of a person. Such action or treatment is considered beneficial for reducing the size of corpulent persons, for exercising the muscles of the body, and for treatment in various cases. Among the objects of the present invention are to provide a machine for giving such bodily treatment, which will be exceedingly effective in action and will serve to act upon a large portion of the body at one time; which is provided with means for readily controlling the pressure of the rolling or contact devices either by an operator or by the person being operated upon; which is provided with means for acting upon opposite sides of the body simultaneously, thereby giving a balanced pressure as well as a balanced massaging action; which is arranged for ready adjustment to different sized persons; and in general, to provide an improved machine of this character such as will be more fully described hereinafter.

In the accompanying drawings illustrating this invention:

Figure 1 is a plan view of the machine; Fig. 2 is a side elevation, parts being shown diagrammatically or broken away for convenience in illustration;

Fig. 3 is a front view of the machine;

Fig. 4 is a rear view, parts also being broken away;

Fig. 5 is a horizontal sectional view showing the base of the machine, parts also being broken away to illustrate the interior construction;

Fig. 6 is a vertical sectional view taken on the line 6—6 of Fig. 5;

Figs. 7 and 8 are details of the rollers and brackets;

Fig. 9 is a partial plan view showing a modified controlling arrangement; and

Fig. 10 is a partial side elevation showing such modified form of control.

The machine comprises a frame 12 having

a base 13 and upper horizontal members 14 and 15, the base and horizontal members being connected by means of posts 16. Vertical shafts 17 and 18 are mounted in the frame 13 and are rotated in opposite directions by means of any suitable driving arrangement. For instance, as shown in Fig. 5, these shafts are provided with worm gears 19 and 20, which are engaged by worms 20' and 21 on a horizontal driving shaft 22, which shaft is mounted in bearings in an oil box 23, and is driven by a motor 24. This motor may be of any suitable type of prime mover, but in the machines which I have actually constructed in accordance with this invention, I have used both alternating and direct current electric motors, the latter usually or frequently being of the reversing type. On account of the worms driving the shafts in opposite directions, the thrust on the driving shaft is substantially equalized. The upper ends of the shafts 17 and 18 are provided respectively with pairs of sprocket wheels 25 and 26. Two chains 27, 27 engage with the sprocket wheels 25, and two other chains 28, 28 engage with the sprocket wheels 26. The chains 27 pass around three other sets of sprocket wheels 29, 30 and 31. The chains 28 pass over three other sets of sprocket wheels 32, 33 and 34. The sprocket wheels 31 and 34 are mounted respectively on arms or yokes 35 and 36, the inner ends of these arms or yokes being fixed to vertical shafts 37 and 38. These shafts are mounted in bearings in the frame and are provided at the bottom with worm gears 39 and 40. These gears are engaged by right and left hand worms 41 and 42 on a horizontal shaft 43, mounted in bearings from the base 13. The shaft 43 is turned for the purpose of rotating the vertical shafts 37 and 38 to swing the arms 35 and 36 in or out as the case may be, for adjusting the rollers or massage devices to the patient or person being treated. For the convenience of the operator, the shaft 43 is provided with a sprocket wheel 44, and a chain 45 leads from this wheel to a smaller sprocket wheel 46, mounted on a stub shaft 47, which shaft is carried in a bracket on one of the posts 16 and is turned by means of a crank 48.

As the arms 35 and 36 swing in or out, the distance between the sprockets carried thereby and the sprockets on the driving shafts

17 and 18 is shortened or lengthened, and therefore means must be provided for keeping the chains tight. For this reason the sprockets 29 and 32 are mounted respectively 5 on shafts 49 and 50 at the outer ends of arms or yokes 51 and 52, such arms or yokes being pivoted upon the shafts 17 and 18, or concentric therewith. Arms 53 and 54 are connected with the upper and lower ends of the 10 shaft 49, and the outer ends of these arms are connected by means of a rod 55. Similar arms 56 and 57 are connected to the upper and lower ends of the shaft 50 and the outer ends of these arms are connected 15 by a rod 58. Ropes or cables 59 and 60 lead from the rods 55 and 58 rearwardly over pulleys 61 and 62 and down to winding drums 63 and 64, to which they are connected. The drums are secured to a horizontal 20 shaft 65 which is mounted in a bracket 66, secured to the rear post 16. Another drum 67 is also secured to the shaft 65 and has a rope or cable 68 and weight 69 connected therewith. The drum 67 is preferably 25 larger than the winding drums 63 and 64, and the arrangement is such that the tension due to the weight will be transmitted to the cables 59 and 60, this tension being sufficient to swing the arms 51 and 52 to take 30 up any slack in the chains, and thereby to keep the chains in proper position. The arms 53, 54, 56 and 57 are provided with stops 70 which engage with the upper frame members to limit the inward movement of 35 such arms.

While the weight 69 will give a certain amount of tension to the roller carrying chains, which tension is transmitted in the form of pressure to the person being operated upon, it is frequently desirable to increase the pressure, and such pressure is preferably regulated by the operator. In order to do this, the shaft 65 is provided with a hand wheel 71 or other convenient 40 means for turning the same. It is also provided with a ratchet wheel 72 which is engaged by a pawl 73 pivoted on the bracket 66, as shown in Fig. 2. This pawl is thrown into and out of engagement by means of an 45 arm 74 which is mounted on the pivot 75 with the pawl and has a weight at its upper end. This arm moves freely between two stop pins 76 and 77 on the side of the pawl. When the weighted upper end is swung 50 against the pin 77, it throws the pawl into engagement and when swung against the pin 76, it tends to throw the pawl out of engagement. By throwing the pawl into engagement and turning the wheel clockwise as seen in Fig. 2, the operator will wind up on the cables 59 and 60, and thereby increase the tension on the carrier chains. When the tension is to be released, the weighted arm 74 is thrown to the left so 55 that it presses against the pin 76, then by

slightly relieving the pressure on the pawl the weight will throw the pawl out of engagement and the hand wheel is released.

The pairs of chains 27 and 28 are respectively provided with brackets 78 and 79 for 70 receiving rollers 80 and 81. These rollers may be made of any suitable material and of such configuration as desired, but in actual practice I have found it desirable to make them cylindrical in form and to make 75 them of wood. These rollers engage with the person to be acted upon, such persons ordinarily wearing a gown of heavy material such as duck in order to prevent the rollers engaging directly with the body. 80 On account of this protection to the body, the pressure on the contact devices or massage devices may be very much greater than if the devices acted directly on the skin. This permits a deeper massage action without 85 any appreciable friction, and thereby prevents abrasion of the skin. I have found the particular construction shown in Figs. 7 and 8 very desirable. In order to make the brackets sufficiently stiff to withstand 90 the considerable pressure and in order to avoid any considerable projections at the ends of the rollers which might injure the person by coming in contact with the arms or other portions of the body, these brackets 95 are made of channels, with the ends 82 bent over to form bearings for the rods 83. These rods are riveted to the bent over ends and are provided with oil holes for oiling the rollers, which turn directly on the rods. 100

The person to be acted upon is supported by a platform, mensa or table 84 which is vertically adjustable to accommodate persons of different heights. This adjustment is provided by having a base 85 which is secured to the main base 13 and is threaded to receive a cylinder 86, which in turn is threaded to receive a stem 87 secured to the platform 84. The threads on the stem and cylinder are pitched in opposite directions 105 and the cylinder 86 is provided with a hand wheel 88 so that by turning this wheel, the platform is moved up and down, the rear end of the platform being provided with guides 89 which engage with the shafts 17 115 and 18 to prevent the platform from turning.

The shafts 90 and 91 at the outer ends of the arms 35 and 36, upon which the outer sprocket wheels are mounted, are provided 120 at their upper ends with combined guards and handles 92 and 93. The horizontal guard portions of these members extend out a sufficient distance so as to prevent the patient from getting his fingers down into the 125 chains and sprockets, and the upper knobs provide handles whereby the patient may support himself in different positions on the platform and may also push against these arms in order to increase the pressure on 130

different parts of the body. Boards 94 and 95 are pivoted to the upper frame members and swing in a horizontal plane, these boards being also used at times to support 5 the arms of the patient, and also serve as abutments for the patient to push against if desired. These arms are provided at their outer ends with pawls 96 which engage with stationary ratchets 97, (Fig. 2) so that the 10 position of the arms may be adjusted as desired and the arms will then remain in adjusted position. Ordinarily these arms will extend forward at an angle of about 45 degrees to the medial line of the machine.

15 The rollers 80 and 81 are approximately 18 inches long and $1\frac{1}{2}$ inches in diameter in my preferred form of machine, and it is the action of these rollers against the body which produces the desired results. The 20 treatment may be taken in the machine in various ways in order to have the rollers act upon different portions of the body. The most common practice is for the person to be operated upon to swing the boards or 25 supports 94 and 95 forwardly and then take a position on the platform facing either to the front or back of the machine as may be desired. The line of rollers will then be tangent, as it were, to the side of the body. 30 The operator then turns the crank 48 so as to swing the arms 35 and 36 inwardly, thereby bringing the sprockets carried thereby toward each other and simultaneously causing the adjacent flights of the chains 27 and 35 28 to wrap around the sides of the body until these flights are brought around the sides of the person and form segments substantially concentric with the body of the patient. In other words, the chains are 40 wrapped around the sides of the person so as to bring the rollers practically in contact with all portions of the body included between the two sets of rollers. Any slack due to the swinging in of the arms 35 and 36 is 45 automatically taken up by the weight 69 acting through the cables and connections above described. The arms 35 and 36 may be swung in a sufficient distance so as to give any desired pressure from forward to back 50 of the person without further tightening of the chains. If it is desired to increase the pressure by tightening the roller bearing chains, this is done by means of the hand wheel 71 in the manner heretofore described. 55 The motor may be started to drive the roller carrying chains or belts either before the person steps into the machine or after the rollers have been adjusted to the body, and the chains may be driven continuously in 60 one direction or the other, or may be reversed or reciprocated as desired. When the treatment is given in this manner, the patient receives a balanced massage treatment which extends entirely around the body and 65 is found to be exceedingly efficient and cal-

culated to give desirable results, particularly in reducing the size of corpulent persons. The machine is also found to be beneficial for therapeutical treatments, stimulation of the action of the organs, and the like. In 70 some instances the patient will sit upon the platform and merely press the back against the rollers. In fact, the machine may be utilized in a large variety of ways in order to give the necessary treatment to different 75 portions of the body. One of the important features of this machine is the balanced action of the rollers or massage devices. When the person is in the machine with the massage devices acting from the opposite sides 80 of the body, the pressure of one set of devices is counteracted by the pressure of the opposite set of devices, thereby giving an exceedingly flexible and yielding action, although one which is exceedingly efficient, 85 and which is, at the same time, agreeable to the person being acted upon.

Although the machine will ordinarily be operated by an attendant, yet in some instances it may be advantageous to arrange 90 them to be operated by the person receiving the treatment. This may be arranged in any convenient manner; for instance as shown in Figs. 9 and 10, a sprocket wheel 98 which corresponds with the sprocket 95 wheel 46 is secured to a shaft 99 mounted in a bracket 100 at the top of the frame, and this shaft is provided with a crank 101. The chain runs over the sprocket wheel 98 to the main sprocket 44, and the crank 100 is positioned at any convenient point so that the person in the machine may turn the same to operate the front swinging arms. In this construction the shaft 65 with its hand wheel 71 and connected devices is positioned at 100 the top of the machine where it can be operated by the person in the machine instead of an attendant. The operation is substantially the same as above described.

Although I have found in actual practice 110 that the machine as shown and described is exceedingly efficient and satisfactory in operation, it is obvious that various changes may be made which will come within the scope of this invention, and therefore I do 115 not wish to limit myself to the exact construction or arrangement herein shown, except as specified in the following claims, in which I claim:

1. In a machine of the character set forth, 120 the combination of a plurality of non-yielding anti-friction massage devices arranged to be applied to opposite sides of the body, means for moving said massage devices, and means for adjusting the pressure of said devices against the body whereby the pressure of the devices on one side of the body will be resisted by the pressure of the devices on the opposite side of the body.

2. In a machine of the character set forth, 130

the combination of a plurality of non-yielding anti-friction massage devices arranged for engagement with opposite sides of the body, means for operating said devices, and 5 means for adjusting the pressure of said devices in a substantially radial manner with respect to the body, whereby the pressure of the devices on one side of the body will be resisted by the devices on the opposite side of the body.

3. In a machine of the character set forth, the combination of a pair of oppositely disposed flexible roller carrying devices, rollers mounted on said devices, tension devices for 15 placing a predetermined tension on said flexible roller carrying devices, and co-acting means for manually increasing the tension on said devices.

4. In a massage machine, the combination 20 of a pair of belts, massage rollers mounted on said belts, take-up devices for said belts, cables connected with said devices, guide sheaves for said cables, drums with which said cables connect, a shaft carrying said drums, a weight connected with said shaft for placing a tension on said cables, a hand wheel on said shaft for increasing the tension on the cables, and means for holding 25 said shaft in adjusted position.

5. In a massage machine, the combination 30 of chains, massage devices carried by said chains, movable take-up sprockets for said chains, tension cables, connecting means between said cables and said sprockets, guide sheaves for said cables, a shaft, drums on 35 said shaft for said cables, another drum on said shaft, a cable connected on said last named drum, a weight carried by said cable, means for manually turning said shaft, a ratchet wheel on said shaft, and a pawl 40 adapted to engage with said ratchet wheel.

6. In a machine of the character set forth, the combination of a frame, massage devices carried by said frame, an adjustable platform 45 at the bottom of the frame, oppositely disposed swinging supports at the top of the frame for supporting the arms of the person in the machine, and means for holding said supports in adjusted position.

7. The combination in a massage machine 50 of the character set forth, of a frame, massage devices carried by said frame, supports pivoted at the top of the frame for supporting the arms of the person in the machine, 55 racks on said frame, and pawls on said supports engaging with said racks and adapted to hold the supports in adjusted position.

8. In a machine of the character set forth, the combination of a frame, oppositely disposed massaging devices carried by said frame, a threaded base mounted on said frame centrally of said massaging devices, a tubular threaded member engaging with said base, a hand wheel for said threaded mem-

ber, a threaded stem engaging with the inner threaded portion of the tubular member, and a platform carried by said stem, said threads being oppositely pitched so that when the wheel is turned the platform will be moved vertically.

9. In a machine of the character set forth, the combination of vertically arranged shafts, massage devices operated by said shafts, worm gears on said shafts, a third shaft arranged adjacent to said gears, bearings for said last named shaft, worms on 70 said shaft engaging with said gears, said worms and gears being pitched in opposite directions to equalize the thrust, and means for turning said worm shaft.

10. In a machine of the character set forth, the combination with the adjustable body treatment device, of means whereby the person in the machine may adjust the treatment devices around the body, and 85 means whereby he may also adjust the tension of the devices.

11. In a machine of the character set forth, the combination with the flexible carriers having non-yielding body treatment 90 devices carried thereby, of means for bringing said devices into operative relation with the body, and means whereby the person acted upon may adjust the tension of said carriers.

12. In a machine of the character set forth, the combination of a frame, oppositely disposed flexible carriers, means for supporting and adjusting said carriers, rollers mounted on said carriers, said adjusting 100 means being arranged to be operated by the person to be acted upon, to bring the rollers into operative relation with the body, and means for adjusting the tension on said carriers, said means also being arranged to 105 be operated by the person being acted upon.

13. The combination of a frame, an adjustable platform at the bottom of said frame, horizontally arranged flexible carriers at the top of the frame, rollers on said 110 carriers, driving shafts for driving said carriers, means for turning said shafts, swinging arms for adjusting the position of the carriers at the front of the machine, shafts carrying said swinging arms, means for 115 turning said shafts simultaneously in opposite directions for adjusting the arms, said means being arranged to be operated by the person to be acted upon, take-up devices for taking up the slack in the carriers and holding them in position, and means operable by the person acted upon for increasing the tension on said carriers whereby the pressure of the rollers against the body may be 120 regulated.

14. The combination of a frame, two shafts arranged vertically at the back of the frame, worm gears on said shafts, a driving

shaft, worms on said driving shaft engaging with said gears, a motor for turning said driving shaft, pairs of sprockets at the top of each of said shafts, chain belts engaging with said sprockets, guide sprockets at the sides of the frame for said belts, swinging arms at the front of the frame, guide sprockets for said belts carried by said arms, swinging arms at the rear of the frame, guide sprockets for said belts carried by said rear arms, rollers or the like carried by said belts and adapted to engage with the opposite sides of the person to be treated, means for swinging said first named arms to bring the rollers into operative relation with the person being treated, tension devices for said last named arms for taking up the slack on the chains and holding them in position, and means co-acting with said tension devices for manually adjusting the tension on the chains.

15. In a massage machine, the combination of oppositely disposed horizontally arranged yielding carriers, non-yielding massage devices mounted on said carriers and adapted to engage with the opposite sides of a person positioned between the carriers, supports for said carriers, a hand wheel adapted to be operated by the person in the machine, connections between said hand wheel and one of said supports for moving the support, whereby the pressure of the massage devices against the body may be adjusted, and a ratchet and pawl associated

with said hand wheel for holding the parts 35 in adjusted position.

16. In a massage machine, the combination of oppositely disposed horizontally arranged yielding carriers, means for moving said carriers in a horizontal direction, non-yielding massage devices mounted on said carriers and adapted to engage with the opposite sides of the body of a person positioned between the carriers, and means which may be operated by the person in the 40 45 machine for adjusting the pressure of the devices against the body.

17. In a machine of the character set forth, the combination of oppositely disposed sets of yielding carriers, non-yielding massage devices mounted on said carriers, means for actuating said carriers in a horizontal direction to cause the massage devices to engage with the opposite sides of the body of a person, a hand wheel adapted to 50 55 be actuated by the person taking the treatment, connections between said hand wheel and one of said carriers, whereby the carrier may be adjusted to adjust the pressure of the devices against the body, a ratchet wheel connected with said hand wheel, and a pawl for holding the wheels in adjusted position.
